[57] **CLAIM**

The ornamental design of a non-slip grip wrap, for use on handles of hand tools, as shown and described.

DESCRIPTION

FIG. 1 is a perspective view of a non-slip grip wrap showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a view of the non-slip grip wrap applied to the handle of a hammer;

FIG. 9 is a view of the non-slip grip wrap applied to the handle of a screwdriver;

FIG. 10 is a view of the non-slip grip wrap applied to the handle of a chisel; and,

FIG. 11 is a view of the non-slip grip wrap applied to the handle of a pipe-wrench.

The broken line showing of the tools in FIGS. 8, 9, 10, and 11 is for illustrative purposes only and forms no part of the claimed design.
